DESIGN FOR A FLASHLIGHT

Jules P. Gits, Chicago, Ill., assignor to Gits
Molding Corporation, Chicago, Ill., a corporation of Illinois

Application December 7, 1939, Serial No. 88,744

Term of patent 7 years

To all whom it may concern:

Be it known that I, Jules P. Gits, a citizen of the United States, residing at Chicago, in the county of Cook and State of Illinois, have invented a new, original, and ornamental Design for Flashlights, of which the following is a specification, reference being had to the accompanying drawing, forming a part thereof.

In the drawing:

I claim:

The ornamental design for a flashlight, substantially as shown and described.

JULES P. GITS.
